UNITED STATES PATENT OFFICE.

HENRY D. JAMES, OF PITTSBURG, PENNSYLVANIA, ASSIGNOR TO WESTINGHOUSE ELECTRIC & MANUFACTURING COMPANY, A CORPORATION OF PENNSYLVANIA;

CHARLES W. BROWN
RHEOSTAT.

No. 926,254.

Specification of Letters Patent.

Patented June 29, 1909.

Application filed July 17, 1905. Serial No. 270,162.

To all whom it may concern:

Be it known that I, HENRY D. JAMES, a citizen of the United States, and a resident of Pittsburg, in the county of Allegheny and State of Pennsylvania, have invented a new and useful Improvement in Rheostats, of which the following is a specification.

My invention relates to rheostats and particularly to devices of this general character which are employed for the control of electric motors and for similar purposes.

The object of my invention is to provide a simple, compact and durable means for effecting variations in the resistance of an electric circuit, and a further object of the invention is to provide means for reversing circuit connections by the movement of a single member that co-operates directly with the resistance elements.

In the accompanying drawing, Figure 1 is a diagrammatic view of an electric motor and a rheostat embodying my invention. Fig. 2 is a side elevation of one of the resistance grids utilized in my invention, and Fig. 3 is an end elevation of a plurality of the grids shown in Fig. 2.

As here illustrated, my invention comprises two groups 1 and 2 of resistance elements, each of which comprises four sets of grids 3 arranged in pairs. Each grid 3 is preferably in the form of an iron casting of zigzag formation, as indicated in Fig. 2, the grids being so connected and insulated that those of each set shall be connected in series, as indicated in Figs. 1 and 3.

Properly fastened to the outer ends and clamped between adjacent terminal portions of the grids, are contact bars 4 of relatively good conducting material, having aligned outer surfaces 5 with which engage the brushes 6 of movable contact devices 7, suitable blow-out coils 8 being provided, if desired. The devices 7 are mechanically connected together but suitably insulated from each other by means of a frame 9, which may be operated by a suitable handle 10. The outer ends of the groups of grids 3 are so connected to the supply circuit 11-12 and to the armature 13 and field magnet winding 14 of a motor 15 that when the contact devices are in engagement with the grid contact terminals 5 of one group the motor will rotate in one direction and when the contact devices are moved to engage with the contact terminals

5 of the other group the direction of the flow of current through the armature will be reversed so that the direction of rotation of the motor armature will be reversed. Obviously, the connections might be so arranged as to reverse the connections to the field magnet winding instead of to the armature and thus secure the same result, as is well known in the art.

When the contact devices 7 are in the position indicated in the drawing, the entire amount of resistance in the group 1 of the resistance elements is included in the motor circuit, and by moving the devices by means of the handle 10 toward the left, the resistance will be gradually cut out. If it is desired to reverse the motor, the contact members 7 will be moved from left to right into engagement with the contact terminals 5 of the group 2 and the motor will then be reversed with all of the resistance of the group 2 in circuit, and this may be gradually cut out by moving the contact members toward the ends of the grids which are connected to the motor and to the external circuit.

It will be understood that this specific arrangement of resistance elements and the structure of the contact devices, in so far as structural features are shown, are merely indicative of any suitable arrangement and means for effecting the desired result and that any suitable means, whereby substantially the same mode of operation and results are secured, is within the scope of my invention.

I claim as my invention:

1. The combination with two groups of resistance grids provided with angular contact terminals clamped between them, and a motor to which said grids are permanently connected, of movable contact devices for engaging either group of grid contact terminals and for varying the number of grids included in the motor circuit.

2. The combination with an electric motor and two groups of resistance grids reversely connected to one member of the motor and provided with contact terminals of better conductivity than the grids, of contact devices for engaging the one or the other group of grid contact terminals, according to the direction of motor rotation desired, and for varying the number of grids in circuit with the motor.

3. A rheostat comprising two groups of

resistance elements disposed in rectilinear alignment with each other and having their outer ends reversely connected to a translating device, and reciprocatory contact devices for connecting either group of resistance elements in circuit and for varying the number of active elements.

In testimony whereof, I have hereunto subscribed my name this 11th day of July, 1905.

HENRY D. JAMES.
